UNITED STATES PATENT OFFICE

WILLIAM TYCHIE, OF GROSSE ISLE, MANITOBA, CANADA

MOWING MACHINE

Application filed January 18, 1927. Serial No. 161,820.

This present invention relates to improvements in a mowing machine, appertaining particularly to a device of this character adapted for attachment to a railway car truck, the cutting mechanism of which is intended, as the car advances along the track to operate on the grass growing at the side thereof.

An object is to provide a mowing machine 10 so mounted on a railway car truck that the cutting mechanism is actuated by the rotation of one of the truck axles, through the medium of gears and a pitman.

Another object is to provide a mowing 15 machine whose cutter bar may be initially positioned at approximately the necessary height and thereafter, while running, adjusted within limits to the desired elevation to compensate for undulations in the land 20 along the track or the like while the vertical hanging of the cutter bar into operative and almost upright position is readily effected on the operation of additional means provided for that purpose.

A still further object is the provision of a 25 device of the character described characterized by structural simplicity, ease and economy of operation and capable of production at a reasonable cost, being thereby rendered commercially desirable.

To the accomplishment of these and related objects my invention resides in the construction, combination and arrangement of parts as shall be hereinafter more fully described illustrated in the accompanying 35 drawings and pointed out in the claims hereunto appended.

The invention will be best understood and can be most clearly described when reference 40 is had to the drawings, forming a part of this disclosure, wherein like characters indicate like parts throughout the several views.

In the drawings:—

Fig. 1 is a plan view of my improved 45 mower;

Fig. 2 is a front elevation thereof; and

Fig. 3 is a sectional detail of a conventional form of clutch operating in the drive mechanism of the device.

No propelling agent has been shown in

the drawings as it is preferred that the truck on which the mower is mounted be not encumbered with such. It is desirable to maintain the weight of the mower at a minimum as its lightness is one of the features of the 55 invention enabling the ready handling of the truck in placing it on or lifting it from the track. Consequently it is intended that the car be drawn by any suitable draft means as for instance a horse or a gas engine traction 60 car or the equivalent, but as the draft means is incidental and does not constitute a part of the invention, but passing mention is made of it.

Particular reference is now had to the 65 drawings: the numeral 4 designating a railway car truck of usual design comprising a pair of side frame members 5 mounted on the axles 6 which are each formed integral with a pair of spaced flanged car wheels 7.

A cradle formed of a spaced pair of cross beams 8 is slung under the truck 4, the beams 8 being bolted to the underside of the frame members 5 and extending out at one side beyond the wheels 7. A pair of arms 9 supported by these cradle beams 8 extend rearwardly to carry a transversely disposed shaft 10 rotatably journaled thereon. One end of said shaft 10 projects over the same side of the truck as do the cradle beams 8, while 70 to the shaft between the arms 9 a gear pinion 11 is keyed with which a gear wheel 12 keyed to the adjacent truck axle 6 meshes.

A transmission housing 14 is supported by 75 the projecting ends of the cradle beams 8 being located exterior of the frames 5 and disposed longitudinally. The main drive shaft 10 continues into the housing where it terminates with a clutch 15 and a bevel gear 16, shown in detail in Figure 3. The manually 80 operated clutch 15 slides longitudinally of the shaft on a key way and is adapted for engagement with the bevel gear 16 which normally runs free.

A transmission shaft 17 carried by bearings 85 in the housing 14, has a bevel gear 18 on one end that meshes with the clutch engaging bevel gear 16 and is provided on the remote end with a crank member 19 that actuates the 90

cutting knife through the medium of a pitman 20.

Configurated on the outer side of the housing 14 near the end receiving the shaft 10, are a pair of lugs 21 through which horizontally aligned perforations 22 are bored to accommodate a bearing pin 23.

The cutter bar 24 of usual design is slung under the head 25 at its inner end to which it is hingedly connected. This head is rigid with the main supporting arm 26 that is pivoted horizontally at its opposite end on the shaft 17 between the crank 19 and the adjacent end of the housing 14.

A brace arm 27 joins the arm 26 near the head 25, its remote end being angular to the body to connect with and pivot horizontally on the pin 23.

The vertical adjustment of the cutter bar is accomplished by raising or lowering the head 25 in a novel way, with the vertical hinging of the bar into upright or almost vertical position being effected by an expedient to be described later. A post or standard 28 is mounted on the outer end of the adjacent cradle beam 8 and acts as fulcrum for a lever 29 that is pivoted to its offset upper end 30. The outer end of the lever 29 carries a chain 31 by which it is connected to the head 25 while from the inner end of the lever 29 a line 32 extends that passes downwardly under a pulley 33 on the beam 8 at the adjacent side of the car, across the vehicle and over a corresponding pulley on the opposite side of the car and terminally connects with the lower end of a manually operated lever 34 the upper or handle end of which is offset on the pivot rod 35 and is provided with dog mechanism to engage the arcuate rack 36. The vertical hinging of the cutter bar-carrying arm 26 by the manipulation of the lever 34 will thus be clearly seen.

Pivoted at its apex to the cutter bar head 25 and at its lower end to the cutter bar frame 24 is a bell crank 37 whose upper end extends substantially above the head 25. A cable 38 anchored thereto passes downwardly under a pulley mounted on the supporting arm 26 and thence to a lever 39 fastening thereto at a point between the fulcrum and the handle end. As in the previous case, this lever is also manually adjusted and is held in any desired position by the action of a spring dog of usual form engaging an arcuate rack 40. Both the lever 34 and the rack 40 are mounted on the cradle beam 8 remote from the driving axle 6 as are the lever 34 and its co-operating rack 36.

The construction and relation of the several parts having been thus described there now follows a brief reference to the use and modus operandi of the invention.

As the car is advanced along the track by any approved draft means, the clutch 15 is thrown into operative position producing

the reciprocation of the knife in the cutter bar through the medium of the pitman 20. If the ground along the track is low the cutter bar is lowered by adjustment of the lever 34 that drops the head 25 while if the bank receeds quickly or enclines sharply upwardly the cutter bar is brought to the proper angular position by manipulation of the lever 39 that hinges the bell crank 37. Thus any and all the variations in the lie of the land alongside the track can be readily cared for by the versatile operations of this improved mowing machine.

From the foregoing description taken in connection with the accompanying drawings, it will be manifest that a mowing machine is provided that will fulfill all the necessary requirements of such a device, but as many changes could be made in the above description and many apparently widely different embodiments of my invention constructed within the scope of the appended claims without departing from the spirit or scope thereof, it is intended that all matters contained in the said accompanying specification and drawings shall be interpreted as illustrative and not in a limited sense.

What I claim as new and desire to secure by Letters Patent is:—

1. A railway mowing machine including the combination of a wheeled truck; a cradle projecting laterally from one side of said truck; a transverse rotatable shaft driven by one of the axles of the wheeled truck; a casing supported at the outer end of said cradle; a supporting arm hingedly mounted on said casing; a cutter bar head carried by said supporting arm; a cutter bar pivoted for vertically swinging adjustment in said cutter bar head; transmission mechanism within said casing and driven by said transverse shaft; and driving mechanism connecting said transmission mechanism with said cutter bar to operate the latter.

2. A railway mowing machine including the combination of a wheeled truck; a cradle projecting laterally from one side thereof; a cutter bar head hingedly mounted at the outer end of said cradle; means for regulating the position of said cutter bar head with respect to said cradle and the wheeled truck; a cutter bar operable in said cutter bar head; means supported by said cradle for operating said cutter bar from one of the axles of said wheeled truck; a casing carried by said cradle for part of the last mentioned means; and means for tilting said cutter bar to different inclined planes independently of the adjustment of said cutter bar head.

In testimony whereof I hereunto affix my signature.

WILLIAM TYCHIE.
